(57) **CLAIM**

The ornamental design for a ruler for displaying fractional and decimal measuring indicia, as shown and described.

DESCRIPTION

FIG. 1 is a top plan view of a ruler for displaying fractional and decimal measuring indicia showing my new design portions not shown for ease of illustration;

FIG. 2 is a bottom plan view thereof;

FIG. 3 is a side elevational view thereof;

FIG. 4 is a front elevational view thereof; and,

FIG. 5 is a perspective view thereof.
